UNITED STATES PATENT OFFICE

2,602,610

JET REACTION PROPULSION APPARATUS
FOR AIRCRAFT

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application March 22, 1947, Serial No. 736,440

1 Claim. (Cl. 244—74)

1

This invention relates to propulsion apparatus of the type which utilizes the reaction from fluid jets under pressure. Such jets are commonly characterized by relatively high velocity and relatively small mass.

It is well established that the reactive force from a high speed fluid jet is proportional to the ejected mass and the velocity of ejection, whereas the energy expended is proportional to the ejected mass and the square of the velocity of ejection. The expended energy is thus vastly greater than the useful reaction, for material ejected at high speed, and it is much more efficient to react against a large mass moving at relatively low speed, rather than against a small mass moving at a very high speed.

It is found, however, that high efficiency for jets of fluid material necessarily implies very high velocity. Consequently, direct reaction from such high speed jets produces only a small thrust in proportion to the amount of energy expended by the ejected material.

It is the purpose of this invention to utilize jets of high velocity and of correspondingly high efficiency to produce reaction indirectly through relatively large masses of fluid material which is caused to move relatively slowly.

The invention further relates to arrangements and combinations of parts which will be herein-after described and more particularly pointed out in the appended claim.

Preferred forms of the invention are shown in the drawings, in which:

Fig. 1 is a partial sectional plan view of a structure embodying this invention;

Fig. 2 is a plan view, partly in section, showing the invention applied to a propelled craft, such as a boat or torpedo;

Fig. 3 is a partial sectional elevation showing the invention applied to aircraft; and

Fig. 4 is a view similar to Fig. 2 but showing a modified construction.

Referring to Fig. 1, a casing 10 of a structure to be propelled is shown as provided with a reaction tube T of relatively large cross section and having a curved reaction portion 12 and a straight rearward discharge portion 14. The tube T is freely open through the casing 10 at its straight intake end portion 15, and air or water may freely enter the tube through said open intake end portion.

One or more nozzles 20 are supported in the intake end portion 15 and are connected by a pipe 21 to a chamber 22 which may contain any suitable fluid under high pressure, such as com-

pressed air, combustion gases, steam or a combustible fluid mixture. Flow through the pipe 21 is controlled by a valve 24.

When this valve is opened, the compressed fluid from the tank or chamber 22 is ejected at high speed from the nozzles 20, as indicated by the arrows a, and immediately encounters the large mass of air or water drawn in through the open intake end portion 15 of the tube T. The energy of the high velocity jets is transferred to the large mass of slow moving fluid in the tube T and imparts thereto a moderate and substantially uniform velocity.

As this large and relatively slower moving mass of fluid reaches the curved reaction portion 12 of the tube T, reaction takes place under most favorable conditions and a very much larger proportion of the jet energy is utilized for reaction and propulsion than could be produced by the jets directly.

If a combustible mixture is used, with air as the reactive fluid, the mixture may be burned at the nozzles 20 to increase the jet energy by combustion gas expansion.

In Fig. 2, the invention is shown embodied in a craft C, such as a boat or torpedo, in which two intake tubes 30 and 31 are provided, one at each side of the craft and each having a pair of associated nozzles 33 connected to a pressure tank or combustion chamber 34. The tubes 30 and 31 extend oppositely across the craft but in different planes, and each tube discharges the slower-moving mass of indrawn fluid through an opening in the side of the rear portion of the craft. This construction permits a relatively long and easy entrance to the curved reaction portion of the tube, and also balances the reaction at the opposite sides of the craft.

A quite similar construction is shown in Fig. 4, but in which, however, the tubes 40 and 41 are in the same plane and connect with a common axial discharge passage 42, so that all of the reaction fluid is discharged axially rearward from the craft C'.

In Fig. 3, the invention is shown as applied to an aircraft. A wing 50 is made hollow for any desired portion of its length and is provided with an intake portion 51, a curved reaction portion 52, and a rearward discharge portion 53. Nozzles 55 are mounted forward of the reaction portion thus provided in the hollow wing, and air, steam or gas at high pressure is delivered to the nozzles 55 from a storage tank 60 through a control valve 61. The tank 60 extends lengthwise of the wing and may be provided with suc-

cessive pairs of nozzles 55 at any desired spacing along the wing.

The high velocity jets from the nozzles 55 deliver their energy to a large mass of air entering through the intake portions 51, and this large mass of relatively slower moving air reacts against the curved portion 52 under very favorable conditions, and provides both forward and lifting forces. A propulsion wing as above described will be provided at each side of the craft, to balance the reaction forces.

The construction shown in Fig. 3 may be streamlined by providing a shield 62, which reduces air resistance and also stiffens the wing construction.

Having thus described several forms of this invention, it will be apparent that each form provides means by which high energy, high velocity jets may be caused to operate efficiently by transferring their excessive energy to relatively slower moving but much larger masses of gaseous or liquid reaction material.

Having thus described the invention and the advantages thereof, it will be understood that the invention is not to be limited to the details herein disclosed, otherwise than as set forth in the claim, but what is claimed is:

In combination with an aircraft body, reaction propulsion apparatus comprising two relatively large and substantially straight open intake passage portions oppositely disposed in said aircraft body and directed inward at opposite sides of said body, a separate curved intermediate reaction passage portion for each intake passage portion and crossing said body from side to side at the longitudinal axis thereof, a separate and substantially straight rearward discharge passage portion for each separate curved reaction passage portion, each set of as-

sociated intake, reaction and discharge passage portions constituting a single continuous passage, the axis of which is disposed in a single plane, and the two single planes of the two continuous passages being superposed adjacent and parallel, with each discharge passage portion opening at the opposite side of said aircraft body from its associated intake passage portion for balanced reactions at opposite sides of the body, and means to inject high velocity fluid jets into said intake passage portions well in advance of the intermediate reaction portions, which jets are directed inward toward said curved intermediate reaction passage portions and accelerate the air mass approaching said curved intake passage portions for the increase of forward thrust activity.

ESTHER C. GODDARD,
*Executrix of the Last Will and Testament of
Robert H. Goddard, Deceased.*
